ALBERT ISENSEE, OF INDIANAPOLIS, INDIANA.

Letters Patent No. 73,897, dated January 28, 1868.

IMPROVEMENT IN BURGLAR-ALARM LOCKS.

The Schedule referred to in these Letters Patent and making part of the same.

TO ALL WHOM IT MAY CONCERN:

Be it known that I, ALBERT ISENSEE, of Indianapolis, in the county of Marion, and State of Indiana, have invented a new and useful Improvement in Burglar-Alarms Connected with a Door-Lock; and I do hereby declare that the following is a full, clear, and exact description of the same, reference being had to the annexed drawings, in which—

Figure 1 is a side elevation showing the internal mechanism of a lock.

Figure 2 is an elevation of the bolt.

Figure 3 is an elevation of the sliding tumbler.

Figure 4, a similar elevation of another plate.

Figure 5 is an elevation of one of the keys.

Figure 6, a plan view of the key, shown in fig. 5.

Figure 7, a side elevation of another key.

Figure 8 is a plan of the same.

Figure 9 is an elevation of the alarm-mechanism.

Figure 10 is an elevation of the alarm-set.

Figure 11 is a perspective view of the bell; and

Figure 12 is a section of the same.

The same letters are employed in the indication of identical parts in all the figures.

A is the case of the lock, and B is the bolt, which is formed as shown in fig. 2. B¹ is an arm projecting from the top of the bolt and supporting the stem B². This stem is surrounded by the spiral spring C placed between the arm B¹ and a projection, D¹, from the sliding tumbler D, the form of which is shown in fig. 3. The slot at D² receives the pin H, on which is hinged the oscillating tumbler E, the form of which is shown in fig. 1. F is a spring, acting on the tumbler E, the other end bearing against the projection A²; a similar spring, D³, acting on the sliding tumbler D, resting against another projection, A¹, on the case A. G is an intermediate stationary plate between the bolt and tumbler E. I have shown but one oscillating tumbler; the number may be increased at will. The pin B³ projecting from the bolt B, passes through the slots E¹ and G¹ in the tumbler and intermediate plate. I is an arm, projecting from the sliding tumbler D through an opening in the end of the case A. This arm actuates the alarm-mechanism, in a manner to be explained hereinafter.

I use two keys, shown in figs. 5 and 7, of which fig. 5 represents the inside key, and fig. 7 the outside key, marked respectively L and K. These keys are, in construction, the reverse of one another. K¹ and L¹ are bits attached to the side of the stem of the key. M is the key-hole passing through the case A.

The operation of this lock is as follows: When the bolt is retracted it is held by the pin B³, in the notch E³ in the end of the slot E¹. The key being inserted, say the inside key L, the ward L² will, as the key is turned, disengage the bolt by raising the tumbler E. The ward L³ acting against the bolt, will then throw it forward one-half its throw, when the bit L¹, coming into action, throws the bolt to its entire projection. The bolt carries with it the sliding tumbler D, and when the bolt is fully thrown, the spring D³, pressing the tumbler downward, the projection A² will catch against the notch D⁴ in the tumbler D. This notch will prevent the bolt from being pressed back entirely, as does also the projection E² above the slot E¹. The bolt will, however, play between the end of the slot E¹ and the projection E², being pressed outwardly by the spring C.

In unlocking, the bit L¹ first moves the bolt back until the ward L² comes into action, when the wards L² and L⁴, acting respectively on the tumblers D and E, engage them from the pin B³ and the projection A², and permit the bolt to be completely retracted.

As the sliding tumbler accompanies the bolt in its movement, the alarm-mechanism having been set when the bolt was thrown, it will be put into action by the arm I striking against a trigger. If a burglar should throw the bolt half back by a hook, he must next raise the tumblers. If he raises the tumbler D, disengaging the notch D⁴, the spring C at once pushes back the tumbler D and arm I, and starts the alarm. If he raises the tumbler E it will strike against the projection D⁵, and thus raise the tumbler D, and produce the same effect.

The following is a description of the alarm: I have shown in fig. 9 one arrangement of clock-work. This may be of any ordinary arrangement, and need not be described. The alarm is enclosed within the bell N, and

the hammer strikes against the projection N^1 , on the inner surface of the bell adapted to receive it. O is the trigger, attached to the double clutch R , by which the action of the spring on the clock-work is prevented until it is released by touching the trigger. P is the alarm-set. It is a plate with a slot, through which passes a stem, P^1 , on which the plate slides. The head is bevelled on the sides, and it has a notch, P^2 , as shown in fig. 10. The lower end of the trigger is bent at right angles, and is received into the notch P^2 when the set P is raised. The bolt being withdrawn, the hooked end of the arm I will stand behind the trigger, the arm passing under the same. Now press up the set P and push the trigger into the notch P^2 holding it up; the clock may be wound up, the set keeping the clutch in the toothed wheel Q . When wound up, by throwing the bolt with the key, the trigger will be carried out of the notch in the set P , and engaging the lower end of the double clutch, which is shown at R , in fig. 9, by dotted lines. When the notch P^2 is disengaged, the plate P will fall, and as the action of the alarm is now only prevented by the hook on the arm I , as soon as the bolt is thrown back or the tumbler D raised, as explained, the arm I disengaging the trigger, the alarm will be sounded.

What I claim as my invention, and desire to secure by Letters Patent, is—

1. The sliding tumbler D and arm I , arranged to operate in combination with the bolt B , substantially in the manner and for the purpose set forth.
  2. The set P , in combination with the trigger O , substantially as and for the purpose set forth.
- In testimony whereof, I have signed my name to this specification in the presence of two subscribing witnesses:

ALBERT ISENSEE.
